GAS MANUFACTURE

Sylvander C. Eastwood, Woodbury, N. J., assignor
to Socony-Vacuum Oil Company, Incorporated,
a corporation of New York

Application January 16, 1953, Serial No. 331,542

5 Claims. (Cl. 48—197)

1

This invention has to do with the manufacture of gas suitable for domestic and commercial use. More particularly, the invention is concerned with the conversion of hydrocarbon stocks, in the presence of hot, solid, contact mass materials, to fuel gases.

In recent years an efficient technique for converting hydrocarbon gases and oils to lower molecular weight materials has been developed and has stimulated considerable interest in the petroleum and related industries. This is the Thermofor Pyrolytic Cracking ("TPC") technique, which has been described in the literature, for example in Oil and Gas Journal, August 26, 1948, and in numerous domestic patents representative of which are: 2,432,503; 2,432,962; 2,436,254; 2,437,383; 2,439,730; 2,444,274; 2,445,554; 2,448,257; 2,448,922; 2,513,294; 2,513,995 and 2,519,315.

In the TPC cracking of some hydrocarbon fractions, and particularly residual stocks, i. e., stocks boiling above about 800° F., to produce gas for domestic and commercial use, more coke is generally deposited on the circulating heat transfer material (HTM) than is required in the burning zone of the system. Naturally, in a cyclic operation, the undue accumulation of coke upon the heat transfer material is disadvantageous and is to be avoided. Such an excessive coke deposition reduces the efficiency of the cracking operation and disturbs the heat balance. Reducing coke formation by reducing the severity of the cracking conditions, is one means for overcoming this circumstance; but this means lessens the efficiency of the operation and, as such, is not a satisfactory solution.

It is an object of this invention to provide an improved process whereby residual hydrocarbon stocks are efficiently converted to fuel gases. It is another object of this invention to so convert residual hydrocarbon stocks, and to recover efficiently the coke or carbon which is deposited upon the heat transfer material, in the form of fuel gas. Other objects will be apparent from the following description.

The present invention involves the use of a single reaction vessel through which a solid heat transfer medium (HTM) is circulated, the HTM serving successively to effect, from the bottom to top of the vessel: cracking and gasification of hydrocarbon charge, reaction of coke to carbon monoxide and hydrogen, and combustion of coke to useful gases and to provide heat to the HTM.

According to the present invention, a residual oil is contacted with an HTM, in countercurrent relation, in a lower section of a reactor, whereupon the residual oil is cracked to methane, ethane, ethylene, hydrogen, etc. and coke is deposited upon the HTM. The HTM upon which coke has been deposited, is removed from the bottom of the reactor and is carried to the

2

top thereof by means of an elevator or other suitable lifting means. In the top section of the reactor sufficient of the coke is burned with air to supply the heat requirements of the process. This heat is stored in the HTM as it is transported by the moving HTM to the lower sections of the reactor where it is needed. Flue gas is removed from the top of the reactor. The hot HTM, still containing part of the coke, flows downwardly to a central section of the reactor where it is contacted with steam or, if desired, with steam containing oxygen or air. In this central section or zone of the reactor, the excess carbon or coke on the HTM is gasified to produce carbon monoxide and hydrogen, i. e., water gas. The gaseous fuel products from the two lower zones of the reactor (water gas and cracked oil vapors) can be removed from the reactor separately or as a mixture.

The invention may be more readily understood by reference to the attached drawing which is an elevational view in section of a preferred embodiment. It will be recognized that the drawing is highly diagrammatic in form.

A granular solid heat transfer material (HTM), such as fused alumina pellets of about 0.3 inch in diameter, is circulated through reactor 1 by means of elevator 2. A plate 3 in the top of reactor 1 provides a bulk supply hopper in the top of the reactor from which hot HTM passes downwardly by feed pipes 4 to provide a compact moving bed in the several zones identified hereinafter. Flow control plates 5, 6 and 7 are provided in the bottom of reactor 1 in order that the HTM can be uniformly withdrawn for return via elevator 2 to the top of the reactor for recycling in the system.

A residual oil boiling above about 800° F. is injected either cold or heated, following passage through a preheater (not shown), from line 8 to a lower section of reactor 1 directly onto the HTM. The residual oil boiling above about 800° F. is distributed across the HTM by inverted angles 9. This lower section of the reactor is designated as a "cracking zone," inasmuch as the temperature therein is sufficient to cause cracking of the oil and such that some coke is caused to be deposited upon the HTM. Among the cracked products which are formed, are: hydrogen, methane, ethane and other gaseous hydrocarbons. The temperature of this zone is maintained at gasification temperatures, for example, between about 1000° F. and about 200° F., preferably 1200-1700° F., with a contact time of about 0.1 to 10 seconds. The cracked products formed in the cracking zone pass upwardly in reactor 1, countercurrent to the HTM and are removed from the reactor at a point below the water gas zone. In the middle zone of the reactor (water gas zone), steam flows downwardly with the HTM as explained above, and removes

excess carbon from the HTM, according to the following reactions:

A mixture of steam and air can be introduced via line 10 in place of steam alone, with the air serving to prevent too much cooling and stoppage of the water gas reaction by burning a portion of the excess coke. The temperature of the water gas reaction zone is kept between about 1200° F. and about 2500° F., and preferably 1600–2000° F., with a contact time of about 0.5 to 60 seconds. Cracked products and the products, CO and H₂, of the water gas reaction are withdrawn from the reactor through line 12.

Above the water gas zone, and above line 10 and inverted angles 11, is a seal zone which is maintained at essentially the same temperature as that of the water gas zone, but which is under a pressure slightly greater than the water gas zone to prevent a large portion of the steam from flowing upwardly through the reactor.

Above the seal zone is a combustion zone wherein carbon or coke is burned off the HTM. Air is introduced into the latter zone through line 13 and is distributed across the downwardly moving HTM by inverted angles 14. The temperature within the combustion zone is maintained above about 1200° F., preferably 1600–2000° F., such that a portion of the carbon or coke on the HTM is converted to carbon oxides. The latter are removed as a flue gas through line 15 at an upper section of the reactor. A back pressure can be applied to line 15 in order to provide the necessary pressure in the aforementioned seal zone. If desired, the seal can be provided by permitting a small portion of the steam (or steam and air) to travel upwardly from the water gas zone through the seal zone to the combustion zone. As coke is burned off the HTM in the combustion zone, the temperature of the HTM is raised to the temperatures desired in the following seal and water gas zones.

It is to be understood that only a portion of the carbon deposited upon the HTM, in its course through the cracking zone, is removed in the combustion zone. Conditions are adjusted to give a partial removal rather than a complete removal since the additional heat is not needed in the process. Then, in the water gas zone the remaining or excess coke stemming from the residual fuel, is converted in the water gas reaction. This two-stage removal of coke is much more efficacious than a one-stage removal by combustion, in that a better heat balance can be maintained in the process and a better conversion efficiency

(i. e., heat combustion gas product)
(i. e., heat combustion liquid feed)

can be obtained.

This invention, as described above, has many advantageous features. For example, removal of flue gas as a separate stream is desirable, particularly if the separation of hydrocarbons from carbon monoxide and hydrogen is desired in subsequent operations. This makes possible reduction in the size and complexity of a product recovery system.

Separation of products and reactants within an individual reaction zone is desirable, because it prevents these materials from entering another

reaction zone wherein they could alter the chemical equilibria established in the latter zone to obtain the desired reactions. This permits closer control of operating variables, such as temperature, pressure and reaction time and results in a more favorable product distribution.

In addition, this invention makes possible a heat balanced unit wherein the heat of combustion of carbon on the HTM is utilized in the water gas reaction. The need for waste heat boilers or any such economizers is eliminated, since direct heat exchange between cold HTM and product gases in the top of the reactor results in substantially complete heat recovery. Also, since quenching of product gas takes place in the reactor, no extraneous quencher is required.

The granular heat transfer material in the process of this invention should be a solid material having a relatively low or substantially no catalytic cracking activity, a high heat absorption capacity and it should be capable of withstanding high temperatures of the order of 2000–2500° F. without severe breakage, cracking or attrition. The material can be non-porous, for example, metallic pieces or balls. Preferably, however, the solid material should be porous, for example, natural clays which have become deactivated so as to have a very low activity as a cracking catalyst. Other materials which can be employed are pumice, mullite, fused alumina, silica, etc. A preferred heat carrying material is granular petroleum coke. The granular material can range in size from about 100 mesh Tyler up to about one inch in diameter, preferably of the order of one-eighth to one-quarter inch in diameter. The term "granular" is employed herein in a broad sense as including solids in various shapes and forms such as pellets, tablets, spheres, and irregular shaped particles.

It is to be understood, however, that although heat transfer materials of little or no catalytic cracking activity are preferred herein, as indicated above, it is also contemplated that catalytically active materials can be used. For example, metallic catalyst compositions, such as nickel, iron, copper and others which promote the desired reactions and yet which retain stability at high temperatures, can be used.

Although the invention is illustrated above by the conversion of a residual fuel of the character shown above, it is to be understood that any hydrocarbon fraction from and including ethane to and including residual fuels can be used herein. As a note of caution, it will be recognized by those skilled in the art that higher temperatures and longer contact times are to be used in converting the lower molecular weight materials, such as ethane, than in similarly converting a residual liquid fuel. Particularly advantageous hydrocarbon charges for the process described and claimed herein, are residual type liquid fuels, and with such charges it is preferred that the following reaction conditions be maintained:

	Tem- perature, ° F.	Reaction time, seconds, in gas phase
Cracking zone.....	1,500	1.
Water gas zone.....	1,800	5.
Combustion zone.....	1,800	Less than 1.

As indicated above, steam or a mixture of steam and air can be charged to the water gas zone. It is to be understood, however, that oxy-

gen can be used in place of air, although the latter is preferred in view of its much lower cost. Similarly, oxygen can be used in place of air in the combustion zone, but air is to be preferred. The dilution effect of nitrogen upon the prime product gases, carbon monoxide, hydrogen and gaseous cracked hydrocarbons, is small and the total product gases have a satisfactorily high heating value for use directly in industrial or utility plants, or can be blended with other gases before put to such use.

I claim:

1. The process which comprises: passing a hot granular solid downwardly in series through a reactor comprising successively a combustion zone, a seal zone, a water gas reaction zone, and a cracking zone; passing a hydrocarbon in direct contact with said solid in said cracking zone under cracking conditions, whereby said oil is cracked to coke and to gaseous products which flow upwardly through said reactor countercurrent to said solid; passing steam in direct contact with said solid in said water gas reaction zone such that said steam flows downwardly therein with said solid, at a temperature between about 1200° F. and about 2500° F. and for a contact time between about 0.5 seconds and one minute, whereby said steam and a portion of the coke deposited on said solid react to form a product predominantly comprised of carbon monoxide

30

and hydrogen, and removing said product from an intermediate section of said reactor between said water gas zone and said cracking zone; maintaining a seal zone above said water gas zone at a temperature substantially the same as that maintained in said water gas zone; passing air into said combustion zone under conditions appropriate for converting a portion of the coke deposited on said solid in said cracking zone, to flue gas and removing said flue gas from an upper section of the reactor above the combustion zone.

2. The process defined by claim 1, wherein the hydrocarbon charge is a residual oil boiling above about 800° F.

3. The process defined by claim 1, wherein a mixture of steam and air is passed into said water gas zone.

4. The process defined by claim 1, wherein said cracking conditions comprise a temperature between about 1200° F. and about 1700° F. and a contact time between about 0.1 and about 10 seconds.

5. The process defined by claim 1, wherein the temperature of said water gas zone is maintained between about 1600° F. and about 2000° F.
